[57] CLAIM

The ornamental design for battery lift handle, as shown and described.

DESCRIPTION

FIG. 1 is a side view, showing the battery lift handle of my new design positioned along a depending rope of indefinite length, the rope shown in broken lines is included for the purpose of illustrating environmental structure only and forms no part of the claimed design.

FIG. 2 is a top view thereto;

FIG. 3 is an end view thereof, the opposite end being identical thereto;

FIG. 4 is a top left hand front perspective view of the battery lift handle of FIG. 1; and,

FIG. 5 is a bottom right hand front perspective view of the battery lift handle of FIG. 1.
